UNITED STATES PATENT OFFICE.

ROBERT LOCHHEAD, OF ANDOVER, MASSACHUSETTS, ASSIGNOR TO TYER RUBBER COMPANY, OF ANDOVER, MASSACHUSETTS, A CORPORATION OF MASSACHUSETTS.

TOBACCO POUCH.

1,409,959.

Specification of Letters Patent. Patented Mar. 21, 1922.

Application filed June 23, 1921. Serial No. 479,756.

To all whom it may concern:

Be it known that I, ROBERT LOCHHEAD, a citizen of the United States, residing at Andover, in the county of Essex and State 5 of Massachusetts, have invented certain new and useful Improvements in Tobacco Pouches, of which the following is a specification.

My invention is a new method of producing 10 a soft rubber tobacco pouch and the pouch produced by this new method.

My new pouch is formed from one piece of semi-cured rubber, which is first made up into a tube preferably seamless, and there- 15 after, by a succession of operations, is formed into a pouch.

In the drawings,

Figure 1 is a flattened section from a tube;

Figure 2 is the same after preliminary 20 trimming;

Figure 3 is an edge view of Figure 2, partly in section, on line 3—3 of Figure 2; Figure 4 is the tube of Figure 3, with a form adjusted within the closed end; and 25 Figure 5 shows the upper or neck part twisted preparatory to being vulcanized to set permanently.

The tube A is made of a diameter suitable 30 for the size of the pouch it is desired to produce. A suitable width, when flattened, as in Figures 1, 2 and 3, is three inches.

The tube is made up of rubber only semi-cured and from this tube a length, say five inches, is cut off and, when flattened, this 35 length will present substantially the appearance and proportions shown in Figure 1. One end of this tube section is then trimmed to curved outline, as shown at a, in Figure 2 and the edges of the curve are coated 40 with rubber cement, and are then brought into butted relationship and caused to unite, as shown in Figure 3. A metal forming block, of a size equal to the size of the tobacco chamber of the finished pouch being placed 45 in the closed end of the tube as indicated at

b, in Figure 4, the portion of the tube projecting above the forming block is creased, that is, indented, longitudinally of the tube, from within, as indicated in dotted lines in Figure 4, to cause the neck of the tube to 50 fold upon the creases. The neck is then rotated a half turn, drawing in the mid-section of the neck and drawing the lower end of the neck over the upper surface of the forming block, as shown in Figure 5, and the 55 neck is then subjected to suitable heat to completely cure the rubber and set the rubber in position permanently.

If desired, a thin strip of rubber may be applied, within the tobacco chamber, along 60 the butted joint, to reinforce the joint.

The finished pouch is perfectly smooth as to its exterior, having no applied bands or lapped joints; is unitary, and the only seam is flat and does not follow, but crosses the 65 curve of the tobacco chamber walls and bisects the flat bottom of the tobacco chamber. The cost of production is greatly reduced and the resulting pouch is stronger and more durable.

I claim:

1. The method of forming a tobacco pouch above described, which consists in cutting a section from a tube of soft rubber, shaping one end of the section to a curvilinear 75 form, uniting the curved edges and forming the chamber over a suitable shaping block by twisting and flattening the open end of the tube and setting the open end in position by vulcanizing.

2. The unitary tobacco pouch above described, formed of a tubular section, one end closed by a seam crossing the bottom of the pouch to form a tobacco chamber, the other end of the tube normally closing by revolving with regard to the chamber.

Signed at Andover, Massachusetts, this 16th day of June, 1921.

ROBERT LOCHHEAD.
